UNITED STATES PATENT OFFICE.

NORMAN C. RENDLEMAN, OF DORMONT, PENNSYLVANIA, ASSIGNOR TO JONES & LAUGHLIN STEEL CORPORATION, OF PITTSBURGH, PENNSYLVANIA, A CORPORATION OF PENNSYLVANIA.

ROLLING WIDE STRIPS.

Application filed July 1, 1926. Serial No. 119,979.

This invention comprises a method of and means for rolling wide strips or shapes of steel from much narrower slabs, and aims to produce relatively wide and thin articles, including thin gauge strips and sheets, at a single heat.

An important object of the invention is the production of sheets such as are required for finishing as tin plates, without the usual number of rolling steps, and without excessive reductions of cross-section demanding a large power outlay or use of an unusual number of roll passes.

Further objects are to enable moderate size slabs to be used for all widths of finished articles, to reduce the wear on the rolls, and to increase and improve the output of the mill.

An illustrative arrangement of a rolling mill plant for carrying out the invention in the production of strips is shown in the accompanying drawings, wherein

Fig. 1 is a plan or layout of a suitable plant;

Figs. 2 and 3 are diagrams showing the shapes of the first two passes of the mill for producing the particular size of strip selected for illustration;

Fig. 4 is a cross-section of the corrugated strip produced by the corrugating rolls;

Fig. 5 is a cross-section of the corrugated strip after passing through the first set of rolling dies in the flattening machine;

Fig. 6 is a plan view and Fig. 7 a front elevation partly in section of a machine for flattening the strip at an intermediate stage of production;

Fig. 8 is an end view of the gearing and driving means for the strip flattening machine; and

Figs. 9 and 10 are cross-sections of the same on the lines 9-9 and 10-10 of Fig. 6, respectively.

In the example shown, the billet or slab 11 (see Fig. 2) may be approximately fifteen inches wide, three inches thick, and six or eight feet long. Such slabs may be readily produced on a blooming or slabbing mill from a twenty inch ingot and sent to the strip mill without reheating.

In the illustrative example, the slab is passed through two sets of corrugated rolls 12 and 13 (see Fig. 1) in quick succession, these rolls being arranged in alinement and

spaced far enough from each other so the slab emerges from one set before it is engaged by the succeeding set. The rolls may be driven by a motor 14 and suitable gearing 15 so designed as to rotate at the desired speed in each successive set, and preferably the speed in each set will be the maximum for the size of the blank. The shapes of the successive sets of rolls are shown in Figs. 2 and 3, the top and bottom rolls of each set preferably being alike so the rolls may be reversed.

The angle of the side walls of the grooves 16 in the rolls 12 and 13 is preferably the same for all the grooves of each pass, and the outer fillets 17 are about the same size in both sets. The inner fillets are smaller in the grooves of the second set, and the side walls are steeper, but the center line length of the blank is the same. In the illustrative embodiment shown, the space between the sides of the grooves of the first set of rolls 12, measured at right angles to the walls, is about one inch; and that between the side walls of the grooves of the second set of rolls 13 is about one-half an inch. Notwithstanding that the thickness of the slab is reduced from 3" to 1" in the first set of rolls, the reduction of cross-sectional area is only about one-third, because the slab measured along its zig-zag centerline is now about 30" from side to side. It is apparent that the reduction in the second pass is also about one-third. These reductions are moderate, and do not involve much loss of power nor wear and tear on the rolls and their bearings.

In the illustrative example, the slab issues from the second pass in a corrugated strip 18 twenty or more feet long, and approximately one-half an inch thick, the overall width being about fifteen inches but the centerline width being about thirty inches. (See Fig. 4.)

Following the second pass, the strip is flattened from corrugated or grooved form in a plate flattener comprising two sets of sector shaped rolling dies 19, 20, through which the strip is fed laterally by any suitable means. The dies 19 of the first set are provided with lengthwise corrugations corresponding in pitch to the corrugations of the strip, but only about one-half as deep, so that the strip 18 emerging therefrom has shallow corrugations, as shown in Fig. 5. The dies 20 of the

second set are smooth, and the strip is discharged therefrom with its corrugations flattened out substantially smooth.

The dies are supported on oscillating shafts 21, 22 (see Figs. 7, 9 and 10) which are mounted in housings 23 and turned by means of couplings 24 driven by sets of gears 25 in a gear housing 26. An idler gear 27 connects the sets of gears 25, and is caused to rotate through part of a revolution by means of the gear 28 and rack bar 29 connected to a piston operating in the hydraulic cylinder 30. Feeding tables 31, 32, are provided for aiding in guiding the strip into the dies 19, 15, 20, respectively.

From the plate flattener the strip is passed through a continuous strip mill having an adequate number of sets of rolls 33 (four being illustrated) for reducing it to the desired 20 gauge. Suitable motors 34 and gearing are provided for driving the rolls 33 at their proper speeds.

The strip thereby produced may be about thirty inches wide and from sixty to two 25 hundred feet long, depending on the gauge or thickness to which it is rolled. The strips may be cut up into plates or sheets, or they may be coiled, as is well understood in the art.

30 The foregoing illustrative example may be considered typical of the mode of operation applicable to the production of various lengths, widths and thicknesses of comparatively wide strips or blanks; but it is evident 35 that the number of passes and the shapes of the corrugating passes, and the construction and arrangement of the apparatus may be modified or changed to suit the character of product and conditions of use to which the 40 invention may be applied.

For example, the cross-rolling may be performed by continuously rotating means disposed upon axes at angles to the direction of movement of the strip.

45 The invention is not restricted to the mode of operation nor to the construction or arrangement of the machine described; but what I desire to secure by Letters Patent is as follows:

50 1. The process of producing wide strips and blanks by first rolling a suitable slab to reduce and corrugate it lengthwise, and thereafter flattening out the corrugations therein by engaging it progressively from one margin to the other and forcing them laterally.

2. Apparatus for producing wide strips and blanks comprising grooved rolls for rolling a suitable slab to reduce and corrugate it lengthwise, and means for flattening out the corrugations therein engaging it progressively from one margin to the other, said flattening means comprising segmental top and bottom die members extending lengthwise of the article.

3. The process of producing wide strips and blanks in three successive operations by first rolling a suitable slab to reduce and corrugate it lengthwise, and next flattening out the corrugations therein by engaging the corrugated slab from end to end and forcing its margins laterally, and thereafter rolling lengthwise the wide strip or blank thus formed to reduce it to the desired thickness. 70

4. The process of producing wide strips 75 and blanks by rolling a suitable slab to reduce it and corrugate it lengthwise, and flattening out the respective corrugations successively to spread the article laterally.

5. The process of producing wide strips 80 and blanks by rolling a suitable slab to reduce it and corrugate it lengthwise, and flattening out the corrugations by successively forcing them laterally to spread them and increase the width of the article simultaneously 85 and uniformly from end to end.

6. The process of producing wide strips and blanks by rolling a suitable slab to reduce it and corrugate it lengthwise and successively flattening out the corrugations 90 individually throughout their entire length to spread the article laterally.

7. The process of producing wide strips and blanks from narrower slabs by rolling them lengthwise to form deep grooves or corrugations, followed by cross rolling to flatten out the corrugations. 95

8. The process of producing wide strips and blanks from narrower slabs by rolling them lengthwise to form deep grooves or corrugations, followed by cross rolling to flatten out the corrugations, and finishing by longitudinal rolling, all of said operations being performed at one heat. 100

9. Means for producing wide strips and 105 blanks from narrower slabs comprising a rolling mill having corrugated rolls for forming longitudinal corrugations in the slab, and a flattener having two sets of oscillating dies arranged parallel to the length of the slab 110 and working in alternation crosswise of the direction of the corrugations to flatten them, thereby widening the article by successive stages.

10. Means for producing wide strips and 115 blanks from narrower slabs comprising a rolling mill having corrugated rolls for forming longitudinal corrugations in the slab, and a flattener comprising oscillating dies working crosswise of the direction of the corrugations 120 to flatten them, thereby widening the article.

11. The combination of a rolling mill for corrugating a slab lengthwise to reduce its thickness, and a flattener having two sets of oscillating dies working in alternation crosswise of the direction of the corrugations, the first set being at a higher elevation to feed into the second by gravity, whereby the slab is flattened by successive means operating on it transversely. 125

12. The combination of a rolling mill for corrugating a blank lengthwise to reduce its thickness, and a flattener having flattening means engaging the blank lengthwise and working crosswise of the direction of the corrugations, whereby the blank is flattened and widened by means operating on it transversely.
13. The combination of a roughing mill having corrugated rolls for reducing and corrugating a blank, a flattening device operating transversely of the length of the blank for flattening out the corrugations to widen the blank, and a rolling mill for reducing and elongating the widened blank.
14. The combination of a roughing mill having corrugated rolls for reducing and corrugating a slab, a flattening mill having complementary rolling means operating transversely of the length of the slab for flattening out the corrugations to form a plate, and a rolling mill for reducing and elongating the plate.
15. The combination of a roughing mill for corrugating a blank lengthwise to reduce its thickness, and a flattener having oppositely disposed members for engaging the blank lengthwise and working crosswise of the direction of the corrugations, whereby the blank is flattened and widened by means operating on it transversely and a rolling mill for reducing and elongating the widened blank.
16. The combination of a reducing and corrugating mill having a series of rolls 12, 13, provided with corrugating grooves, a flattening device comprising successive transversely operating rolling means 19, 20, and a rolling mill having its rolls 33 arranged for operating in a direction at right angles to that of the flattening device, substantially as described.

In testimony whereof, I have signed my name to this specification.

NORMAN C. RENDLEMAN.
